UNITED STATES PATENT OFFICE.

DENVER M. WRIGHT, OF ATLANTA, GEORGIA.

BELT-MAKING MACHINE.

1,297,770.

Specification of Letters Patent.

Patented Mar. 18, 1919.

Application filed May 15, 1918. Serial No. 234,820.

To all whom it may concern:

Be it known that I, DENVER M. WRIGHT, a citizen of the United States, residing at Atlanta, in the county of Fulton, in the State of Georgia, have invented certain new and useful Improvements in Belt-Making Machines, of which the following is a specification.

The object of this invention is to provide a machine for use in the manufacture of leather straps or belts composed of a plurality of links, and is designed to unite the several links to form the complete strap or belt.

A further object is to provide a machine for this purpose which shall be exceedingly simple in construction and thoroughly efficient in operation.

The invention is graphically illustrated in the accompanying drawings, which show one form of embodiment capable of carrying out the underlying principles of my invention. Like reference-characters denote corresponding parts throughout the several views. The different figures of the drawings may be briefly described as follows:

Figure 1 is a side elevation of my machine;

Fig. 2 is a top plan view thereof;

Fig. 3 is a view in end elevation, looking at the left hand of Fig. 1;

Fig. 4 is a plan view of one of the links of the strap or belt before it is folded and assembled with the remaining links to form the strap;

Fig. 5 is a view in side elevation of a belt or strap made by my machine;

Fig. 6 is a fragmentary longitudinal sectional view taken along the line 6—6, Fig. 2;

Figs. 7 and 8 are similar views, showing the position of the parts at successive stages in the operation of the machine;

Fig. 9 shows, in front or rear elevation, a belt or strap made by my machine; and

Fig. 10 is a top plan view of the rigid link-supporting member, of the machine.

Referring, now, in detail to the drawings:

The machine may be provided with a suitable supporting base, in this instance an angle-iron having a bottom flange 1 adapted to be secured to a stationary support 2, as by bolts passing through bolt-holes 1^a, and a flange 3 perpendicular to the bottom flange 1.

Secured, as by rivets 4, or the like, to the

flange 3 of the supporting base is a bracket 5 carrying a shelf 6 parallel with the base flange 1.

Carried at one end of said shelf is a rigid link-supporting member 7, in the form of a plate bifurcated at 8 to form legs 9, 9, which are bent upward at their free extremities, to form hooks 10, 10, to engage a leather strap-link A (hereinafter to be more particularly described) in a manner to appear later in the description.

Coöperating with and disposed over the plate 7 is a resilient spring-metal member 11, screws 12 passing through one end of the plate 7 and member 11 to secure the same to the shelf 6. The resilient member 11 is bifurcated similarly to the plate 7, to provide two arms 13, 13, which are bent so as to incline upward from the legs 9, 9 of the rigid link-supporting member 7, said arms terminating in curved beaks 14, 14 arching over the upturned ends 10, 10 of the rigid link-supporting plate 7.

Reciprocable in suitable bearings 15, 15 carried by the shelf 6 is a rod 16 carrying, at one end thereof, an end plate 17 disposed in a plane perpendicular to the shelf 6. The plate 17 is preferably removable, and, to this end, a locking-nut 18 is screwed on the reduced threaded end 16' of the rod 16, thereby clamping the plate rigidly to the rod.

The end plate 17 is provided with two apertures 19, 19, to receive tubular members 20, 20, constituting sleeves encircling the legs 9, 9 of the plate 7 and the resilient legs 13, 13 of the plate 11. The diameter of the tubular members 20, 20 is such that, when the rod 16 is reciprocated so as to move the members 20, 20 toward the beaks 14, 14 of the resilient legs 13, 13, the latter will be pressed downward toward the upturned ends or hooks 10, 10 of the rigid plate 11 (as shown in Fig. 8). The tubular members 20, 20 may be brazed or welded to the end plate 17, or otherwise secured thereto.

Between the right hand bearing 15 in Fig. 1 and a collar 21 fast on the rod 16 is an expansion spring 22 coiled around the rod, and tending to move the same toward the right in Fig. 1.

Limiting movement of the rod 16 in a direction toward the right in Fig. 1 is a collar 23 provided with a set-screw 24, whereby the collar may be adjusted on the rod 16. The collar 23, by abutting the bearing 15, limits

movement of the rod toward the right in Fig. 1.

Suitable means for reciprocating said rod are provided, and, in this instance, such means preferably comprise a bell-crank lever 24 fulcrumed at 25 to the bracket 5, the shorter arm of the lever being provided, at its free extremity, with a yoke 26 embracing a pin 27 projecting through a block 28 and through the rod 16. The block slides on the shelf 6 and moves with the rod 16. Pressing downward on the lever 24 will reciprocate the rod 16 to the left in Fig. 1, as shown in dotted lines.

One of the links of the belt or strap is shown in Fig. 4, and is preferably of leather. As shown, the link A is a blank, which may be cut or stamped out of a sheet of leather by suitable cutting-dies, and has, preferably, rounded or curved ends a , a' , and the sides of the blank, intermediate their length, are curved inward, as shown at a' , a' . The blank is slotted, at a^2 , the slit commencing at one of said curved ends a and following an imaginary line dividing the blank longitudinally into halves, and terminates, at the center of the blank, in an expanded, substantially elliptical aperture a^3 in alignment with the curved portions a' , a' of the sides of the blank. The blank is also provided, toward each end, with a pair of transversely-aligned holes a^4 , a^4 .

In operation, the link A is folded by the operator along the dotted line shown in Fig. 4, so that the pairs of apertures a^4 , a^4 and a' , a' register. Then the operator places one of the fingers of one of his hands on the resilient arms 13, 13 and presses the latter toward the arms 9, 9, and with the fingers of his other hand pushes the folded blank onto said arms 13, 13 and 9, 9, which thereupon project through the registering holes a^4 , a^4 and a' , a' , of the belt-link A. The operator then pushes the folded link A along the arms 13, 13 and 9, 9 until the link rests against the end-plate 17.

Then, the operator takes a second, unfolded link A and places the same on the hooks 10, 10, which engage the holes a^4 , a^4 in the split end of the blank A, which latter is thereby suspended from the arms 9, 9, as is clearly shown in Figs. 6, 7 and 8. Care must be taken to place this link A on the hooks 10, 10, so that the split end of the link is adjacent the hooks; because, if the link A were reversely disposed on the hooks, i. e., with the unsplit end adjacent the hooks, it would be impossible to operate the machine.

Lever 24 is now moved downward, which reciprocates the rod 16 in the direction of the arrow in Figs. 1, 7 and 8. Fig. 6 represents the position of the parts at the beginning of movement of the rod 16. Fig. 7 represents the position of the parts when the rod 16 has moved sufficiently to bring the

folded blank A into contact with the other, unfolded blank A suspended from the hooks 10, 10—the end-plate 17 pushing the folded blank along the arms 9, 9 and 13, 13 and the tubular members 20, 20 impinging the resilient arms 13, 13 to press the same downward toward the hooks 10, 10. Fig. 8 represents the position of the parts when the rod 16 has reached the limit of its movement in the direction of the arrow. During this latter movement, the folded blank A has been forced, by the end-plate 17, onto what may be called the legs of the unfolded blank, i. e., those portions of the unfolded blank on each side of the split a^2 ,—such legs passing through the registering holes a^4 , a^4 in the folded blank A (as shown in Fig. 8). As soon as the lever 24 is released, the spring 22 returns the rod 16 and, with it, the end-plate 17 and tubular members 20, 20 to normal position, whereupon the spring-metal or resilient arms 13, 13 spring away from the hooks 10, 10 (as shown in Fig. 1). The united blanks may now be removed from the machine, and the unfolded blank A, whose bifurcated portions have thus been reeved through the registering openings a^4 , a^4 of the folded blank, is now, in turn, folded by the operator so that its two pairs of transversely-aligned holes a^4 , a^4 register; whereupon, this newly-folded blank A is, in turn, disposed on the machine (as shown in connection with the folded blank in Fig. 6), and a new blank A (unfolded) is disposed on the hooks 10, 10, and the operation of the machine repeated; and so on, until the necessary number of links have been united to form the desired belt or strap.

Having thus fully described my invention, the many advantages thereof will be apparent, especially to those skilled in the art to which it pertains. Many changes, especially in detail, may be made in the physical embodiment of my invention, it being understood that I am entitled to a fair range of equivalents, according to the scope of my invention, and the spirit of the appended claims.

Having thus fully described my invention, what I claim as new and desire to secure by Letters Patent is:

1. In a machine for making belts or straps composed of flexible links, the combination, with two rigid hook-carrying members, of two coöperating resilient hook-carrying members disposed over said first-mentioned members, and mechanism for flexing said resilient members toward said rigid members, including a reciprocable rod.

2. In a machine for making belts or straps composed of flexible links, the combination, with two rigid hook-carrying members, of two coöperating resilient hook-carrying members disposed over said first-mentioned members, and mechanism for flexing said

resilient members toward said rigid members, including a reciprocable rod and an end plate carried by said rod.

3. In a machine for making belts or straps composed of flexible links, the combination, with two rigid hook-carrying members, of two coöperating resilient hook-carrying members disposed over said first-mentioned members, and mechanism for flexing said 5 resilient members toward said rigid members, comprising a reciprocable rod, an end plate carried by said rod and through which said hook-carrying members loosely project, and tubular members carried by said end 10 plate and encircling said hook-carrying members.

4. In a machine for making belts or straps composed of flexible links, the combination, with two rigid hook-carrying members, of two coöperating resilient hook-carrying members disposed over said first-mentioned members, and mechanism for flexing said 20 resilient members toward said rigid members, including a reciprocable rod, and a lever for reciprocating said rod in one direction.

5. In a machine for making belts or straps composed of flexible links, the combination, with two rigid hook-carrying members, of two coöperating resilient hook-carrying 25 members.

members disposed over said first-mentioned members, and mechanism for flexing said resilient members toward said rigid members, including a reciprocable rod, a lever for reciprocating said rod in one direction, 35 and means for automatically restoring said rod to normal position.

6. In a machine for making belts or straps composed of flexible links, the combination, with a plate bifurcated longitudinally to 40 provide two rigid arms, of a second plate disposed over said first-mentioned plate and similarly bifurcated to provide two resilient arms bent so as to incline upward from said first-mentioned arms, and mechanism 45 for flexing said resilient arms toward said rigid arms, including a reciprocable rod.

7. In a machine for making belts or straps composed of flexible links, the combination, with two rigid, hook-carrying arms, of two coöperating resilient hook-carrying arms disposed over said rigid arms, and mechanism for flexing said resilient arms toward said 50 rigid arms.

In testimony whereof, I affix my signature in the presence of two witnesses.

DENVER M. WRIGHT.
